UNITED STATES PATENT OFFICE.

ISAAC N. MATLICK, OF EDINA, MISSOURI, ASSIGNOR OF ONE-HALF TO
J. N. PRATHER, OF SAN JOSÉ, CALIFORNIA.

ELEVATOR AND CONVEYER.

SPECIFICATION forming part of Letters Patent No. 289,291, dated November 27, 1883.

Application filed April 21, 1883. (No model.)

To all whom it may concern:

Be it known that I, I. N. MATLICK, a citizen of the United States, residing at Edina, in the county of Knox and State of Missouri, have invented certain new and useful Improvements in Elevators and Conveyers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a side view. Fig. 2 is a top view, and Fig. 3 is a cross-section.

This invention has relation to elevators and conveyers for hoisting weights and carrying them to the place of deposit; and it consists in the construction and novel arrangement of parts, as will hereinafter be fully described and specifically claimed.

Referring by letter to the accompanying drawings, O designates a frame for field use, the uprights of which are mounted on runners o, and are connected by suitable girders and braces, as shown, of dimensions of a size suitable to permit the loaded wagon to be driven under it.

A designates the carrier-frame, composed of two scantlings of the desired length, secured together at their ends in any suitable manner, with an intervening space, a, in which the hanger B' of the carrier B travels when the device is operated to carry the weight. At its upper end the hanger B' is provided with a shaft, b, on which, at opposite sides of the hanger, are journaled two flanged wheels, ll, the flanges being at their inner ends. The lower end of the hanger B' is provided with a pulley, m, and an eye, t, for attaching the rope x thereto. The wheels ll travel on the track or rails r of the carrier-frame A, which is supported

in an inclined position in the frame O by bails p and ropes x' x'' and i i', as shown.

C designates a movable pulley, around which the rope x, connected at t, passes, thence up over the pulley m, and along the carrier-frame A to the pulley E at its upper end, over this pulley E, and down to the pulley S, where the hoisting-power is attached. The power applied will first raise the weight or load perpendicularly to the point t, and it will move the carrier B along the carrier-frame or elevator-way to its upper end at E, where the load will be detached, the power released, and the carrier will run back to place at the lower end of the carrier-frame. By the employment of the movable pulley C the force of the power is doubled.

When it is desired to use the apparatus in a barn or building, the frame O should be dispensed with and the carrier-frame and carrier erected therein in any suitable manner that will preserve the incline of the carrier-frame.

Having thus fully described my invention, what I claim, and desire to secure by Letters Patent, is—

1. The incline carrier-frame A, having the pulley E at its upper end, and the bails p, for suspending it, in combination with the carrier B, having hanger B', wheels ll, and pulley m, and the ropes x x' x'' and i i', and pulleys C and S, substantially as specified.

2. The incline carrier-frame A, having the pulley E at its upper end, and the bails p, for suspending it, in combination with the carrier B, having hanger B', wheels ll, and pulley m, and the ropes x x' x'' i i', and pulleys C and S, with the removable frame, substantially as specified.

In testimony whereof I affix my signature in presence of two witnesses.

ISAAC N. MATLICK.
